TIE LOCKING DEVICE

Perley D. Smith, Methuen, Mass.

Application July 13, 1934, Serial No. 735,022

9 Claims. (Cl. 24—87)

This invention relates to locking devices for ties known as four-in-hand ties and has for its object the production of an inexpensive device which when used in connection with a tie of this character will retain the loop thereof well up in the collar and prevent any downward slipping thereof relatively to the other parts of the tie.

Another object is to provide means on said device for preventing any side movement of the rear portion of the tie relatively to the front portion thereof, thus keeping the rear portion directly behind the front portion in its proper position.

These objects are attained by the mechanisms illustrated in the accompanying drawing.

15 For the purpose of illustrating the invention, one preferred form thereof is illustrated in the drawing, this form having been found to give satisfactory and reliable results, although it is to be understood that the various instrumentalities of 20 which the invention consists can be variously arranged and organized, and the invention is not limited to the precise arrangement and organization of these instrumentalities as herein shown and described except as required by the scope of 25 the appended claims.

Of the drawing

Figure 1 represents an elevation of a portion of a four-in-hand tie and showing applied thereto a tie lock embodying the principles of the present invention.

Figure 2 represents a side elevation of said tie lock.

Figure 3 represents a front elevation of a modification of said tie lock.

35 Figure 4 represents a side elevation of same.

Figure 5 represents a horizontal section on line 5, 5 on Fig. 2.

Figure 6 represents an elevation of another modification of said tie lock.

40 Figure 7 represents a side elevation thereof, and Figures 8, 9 and 10 represent respectively, a plan, a front elevation, and a side elevation of another modification of the tie lock.

Similar characters indicate like parts throughout the several figures of the drawing.

In the drawing, 10 is a wire having at its upper end a tapered point 11 and at its lower end a tapered point 12 extending laterally from the body portion of wire 10 and joined thereto by a loop 13, all as shown clearly in Fig. 1 of the drawing.

Between the tapered points 11, 12 the wire 19 is bent as shown in said Fig. 1 to form a stop member 14 extending laterally from the opposite sides of said wire 10.

55 The opposite wings of the stop member 14 are

preferably bent rearwardly, thus forming an arcuate structure as shown in Fig. 5, which is adapted to partially enclose the rear portion 15 of a four-in-hand tie to prevent side play thereof.

This arcuate stop member 14 is positioned immediately beneath the knot 16 of the tie and prevents said knot 16 from moving downwardly.

The upper pointed end 11 of the wire 10 is disposed in the upper portion of the part 15 of the tie and when the stop member 14 is in proper position relatively to the knot 16, the tapered point 12 is inserted in the rear portion 15 of the tie, as shown in Fig. 1.

When the tapered point 12 is thus inserted in the part 15, the wire 10 cannot move downwardly 15 and as the arcuate stop member 14 is in contact with the knot 16, said knot will be retained well up in the collar and cannot slip down exposing the collar button, which exposure would be very objectionable.

When the knot 16 slips down on the part 15 of a four-in-hand tie it gives an unkempt appearance and this condition can be effectually overcome when the device embodying the present invention is used, as described.

20 The device may be made of a single wire 10 as shown in Figs. 1, 2 and 5, or the arcuate stop member 14 may be made of a separate band 17 of metal soldered to the wire 10, as shown in the other figures of the drawing.

If preferred, the tapered point 12 may extend perpendicular to the body portion of wire 10 and be connected thereto by a reverse bend 18, all as shown in Figs. 3 and 4.

When desired the tie lock may have its tapered point 12 extending downwardly and connected to the body portion of the wire 10 by an S-shaped bend 19, as shown in Figs. 6 and 7.

In this form of lock the tapered point 12 is inserted in the part 15 until the cloth of such 40 part reaches the upper bend 20, thus preventing any downward movement of the lock.

A simpler form such as shown in Figs. 8, 9 and 10 may also be used to advantage.

In this modified form the tapered point 12 is 45 inserted into part 15 of the tie until the cloth of said part contacts with the stop member 14, thus preventing downward movement of the locking device.

When this locking device is used on a four-in-hand tie, the tie will always be retained in proper position relatively to the collar and present a tidy appearance, and give the wearer an appearance of being carefully and properly dressed.

It is believed that the operation and many 55

advantages of the invention will be understood without further description.

Having thus described my invention, I claim:

5. 1. A tie locking device consisting of a horizontally disposed arcuate member having extending upwardly and downwardly from a central portion thereof a wire having sharpened pin points at opposite ends.
10. 2. A tie locking device formed in one piece consisting of a horizontally disposed arcuate member having extending upwardly and downwardly from a central portion thereof a wire having sharpened pin points at opposite ends.
15. 3. A tie locking device consisting of a narrow transverse stop member the ends of which are curved rearwardly and from a central portion of which extends upwardly and downwardly a wire having sharpened pin points at opposite ends.
20. 4. A tie locking device comprising a straight wire having at its upper end a tapered point and at its lower end a tapered point perpendicular to the body portion of said wire combined with curved wings extending laterally from said straight wire.
25. 5. A tie locking device comprising a wire having at its upper end a tapered point and at its lower end a tapered point perpendicular to the body portion of said wire and formed integral therewith, the vertical portion of said wire having aligned stop projections curved rearwardly from the opposite sides thereof.

6. A tie locking device comprising a wire having at its upper end a tapered point and at its lower end a tapered point perpendicular to the body portion of said wire, said wire being provided with means for straddling and preventing side movement of the rear depending part of the tie.

7. A tie locking device consisting of a horizontally disposed arcuate member having extending upwardly and downwardly from a central point thereof a wire having sharpened pin points at opposite ends, the lower portion of said wire having an S-shaped bend therein.

8. A tie locking device consisting of a horizontally disposed arcuate member having extending upwardly and downwardly from a central point thereof a wire having sharpened pin points at opposite ends, the lower portion of said wire having its pointed end perpendicular to the body portion thereof.

9. A tie locking device consisting of a horizontally disposed arcuate member having extending upwardly and downwardly from a central point thereof a wire having sharpened pin points at opposite ends, the lower portion of said wire having a reverse bend therein terminating in a lateral pointed end.

PERLEY D. SMITH.
